UNITED STATES PATENT OFFICE.

HERBERT W. REEL, OF CHICAGO, ILLINOIS, ASSIGNOR TO UNITED STATES GYPSUM COMPANY, OF CHICAGO, ILLINOIS, A CORPORATION OF ILLINOIS.

FLOOR CONSTRUCTION.

Application filed April 13, 1925. Serial No. 22,525.

This invention relates to improvements in building construction and more particularly to a floor construction which can also be employed to roofs if desired.

5 In the erection of poured composition floors or roofs it is customary to build a false work, place the domes for forming voids in the slab, and the desired reinforcements thereon, then pour the plastic mixture thereover, and after 10 the mixture becomes hardened remove the false work, lay the floor finish or water proofing on the upper side, as the case may be, and plaster or paint the under side, as desired. As the upper surface of the false work be- 15 comes the mold or form for the under side of the floor or roof and forms the ceiling of the room below, it requires careful selecting, fitting and erecting of this part of the false work to make a uniformly smooth ceiling or 20 under surface.

It is an object of this invention to provide a floor or roof construction that will obviate the time and trouble of selecting and fitting the body of false work as well as provide 25 means for evenly spacing the domes from each other and which will present a smooth even under side of the same character throughout to form a ceiling the decoration of which may be accomplished with or without 30 plastering.

Reference is made to the accompanying sheet of drawing illustrating a preferred form of this invention, and it is understood that minor detail changes may be made without departing from the scope thereof.

In the drawing:

Figure 1 is a view in perspective, partly in section of a portion of a floor or roof constructed in accordance with this invention. 40 Figure 2 is an enlarged detail view in vertical section, illustrating the first step employed in erecting such a floor or roof.

Figure 3 is an enlarged detail view in perspective of the improved dome employed in 45 this construction, with the adjacent end in vertical sections.

Figure 4 is an enlarged detail view in perspective of the improved spacing member employed in this construction, with the adjacent 50 end in vertical section.

In carrying out this invention it is preferred to employ domes of plastic material for providing the voids in the body of the poured material, such as illustrated, and 55 which possess a smooth even under surface

to which plaster will readily adhere. Improved spacing members of calcined gypsum are employed which not only serve as a centering for the domes but also possess an even under surface to which plaster will readily adhere.

To construct a floor or roof in accordance with this invention a false work or temporary support is erected having spaced apart parallel members 1 the upper surface of which are in the plane of the under side of the floor or roof which forms the ceiling of the room below. The domes 2 are placed thereon with their longitudinal edges supported upon the edges of the parallel members 1 one behind the other in a continuous line, a series of spacing members 3 are then laid upon the supporting members 1 in contact with the longitudinal edges of the domes 2 and then another series of domes are placed along the opposite sides of the spacers 3 and in contact therewith, as shown in Figure 2. This simple false work then supports the domes and spacers which form the ceiling of the room below in the desired plane of such ceiling and which act as the bottom of the mold or form for the plastic body. Reinforcement, such as metal rods 4 are then placed in position between the domes and the plastic body 5 then poured over and between the domes 2 and leveled thereabove in the desired plane of the floor or roof and allowed to harden. When completely hardened the false work is removed and the floor finish or roof water proofing is added to the upper surface.

The domes 2 and spacers 3 with or without a fibrous covering are both preferably made of calcined gypsum which has been cast or otherwise formed while plastic into the desired shapes. The upper longitudinal edges 95 of the domes are preferably beveled and a longitudinal groove formed along each longitudinal side adjacent to the lower edge to key same to the plastic body subsequently poured around the voids. The spacers are preferably of the same length as the domes and are constructed of a width equal to the desired space between the lines of domes, and the spacers are provided with a longitudinal groove along each longitudinal edge with the 100 top surface narrower than the lower to provide means of keying the spacer to the plastic body.

In order to protect the surfaces and insure the shape, the spacers 3 are constructed 110

in the manner illustrated in the enlarged view, Figure 4, in which the calcined gypsum or composition body 5 is covered with fibrous covering sheets 6 and 7 adhering thereto, the bottom cover sheet 6 passing over the under surface with longitudinal side margins extending about the grooved edges 8 onto the upper surface of the body and the top cover sheet 7 adhering to the upper surface engages and is secured to the overlapping upper margins of the bottom sheet by a portion of the body material or other adhesive. The sharp corners at the upper and lower longitudinal edges resulting from the groove 8 are fragile and readily broken unless protected by a covering which will insure the key on the upper side and an even line of jointure to the edges of the domes on the under side.

20 In accordance with this invention the top, bottom and longitudinal sides of the dome 2 are also covered with fibrous covering sheets 9 and 10 adhering thereto the side margin of which overlap in the longitudinal groove 11 formed along each side adjacent to the lower edge, with the lower edge of said groove preferably aligned below the upper surface of the spacers 3 when in place on the false work. This fibrous covering insures a continuous square edge on the lower side of each dome, so that when the false work is removed, the bottom surfaces 6 of the spacers 3 and bottom surfaces 10 of the domes 2 will both be protected by the same character of covering material separated by straight lines where they join each other. Such an under surface is not unsightly for a ceiling and as it is protected by the fibrous sheets adhering to the bodies of the domes and spacers it may 40 be left in that condition or may be painted, papered or otherwise decorated as desired, furthermore, the fibrous covering adhering to the bodies of the domes and spacers provides a surface to which plaster will readily bond without further treatment; if it is desired to apply a coat of wall plaster to the ceiling.

What I claim is:

1. A roof or floor of poured plastic material embedding on the under side thereof alternate contacting series of preformed gypsum domes and gypsum spacers of the same material each having longitudinal grooves in the adjacent surfaces for keying the plastic

material thereto, the spacer being wider at 55 the bottom than at the top to permit the plastic material to flow into the longitudinal keying groove and fitting closely between the domes at the bottom, whereby a smooth uniform under surface of homogeneous material 60 is provided.

2. A spacer for poured roof or floor construction formed of plastic material having a fibrous covering adhering to the longitudinal surfaces, said fibrous covering bonding 65 with the plastic material, said spacer being of greater width than thickness, and having grooves along the opposite covered longitudinal narrower sides to form key ways.

3. A spacer for poured roof or floor construction formed of plastic material having a fibrous covering adhering to the longitudinal surfaces, the top surface being of less width than the bottom and the longitudinal sides being of considerable less width than 75 the other two surfaces, and a groove along the longitudinal sides for keying the roof or floor body material thereto.

4. A spacer for poured roof or floor construction to be embedded upon the under side 80 thereof between domes, formed solid from plastic material said spacers being of relatively greater width than thickness and having less width of upper surface than bottom surface with a groove along each longitudinal edge extending from the corners of the upper surface to the corners of the bottom surface, and a fibrous cover sheet adhering to the bottom and grooved surfaces overlapped and secured to a fibrous cover sheet adhering to the 90 top surface.

5. In a roof or floor of poured plastic material, the combination with spaced apart domes of plastic material and having a fibrous covering, of flat spacers of similar plastic material covered with a fibrous coating adhering thereto, the bottom face of the spacer being wider than the top one with longitudinal grooved edges so that the bottom surface of the spacer will contact with the 100 opposite domes and space them apart, and the upper surface of the spacer will be at a distance from the adjacent edges of the dome so that a key of plastic material will flow into the longitudinal grooves of the spacer, the 105 plastic material bonding with the fibrous covering of the spacer and the domes.
